UNITED STATES PATENT OFFICE.

JAMES H. SWINDELL, OF PITTSBURG, PENNSYLVANIA.

GAS-PRODUCER.

No. 814,249.

Specification of Letters Patent.

Patented March 6, 1906.

Application filed December 13, 1904, Serial No. 236,650.

To all whom it may concern:

Be it known that I, JAMES H. SWINDELL, a resident of Pittsburg, in the county of Allegheny and State of Pennsylvania, have invented certain new and useful Improvements in Gas-Producers; and I do hereby declare the following to be a full, clear, and exact description of the invention, such as will enable others skilled in the art to which it appertains to make and use the same.

My invention relates to an improved gas-producer, and more particularly to a suction gas-producer for gas-engines, the object of the invention being to provide improvements of this character of compact form, automatic in its control of the gas produced, and of simple and durable construction.

A further object is to provide improved steam-generating and automatic means for controlling its supply as well as the air-supply to the combustion-chamber.

A further object is to provide improved construction of combustion-chamber, cooler, scrubber, and purifier, improved water-seal pans for the ash-pit and bottom of cooler, the latter permitting the removal of tar without disturbing the operation of the apparatus, and various other improvements in construction and operation, which will hereinafter appear.

With these and other objects in view the invention consists in certain novel features of construction and combinations and arrangements of parts, as will be more fully hereinafter described, and pointed out in the claims.

In the accompanying drawings, Figure 1 is a view in vertical longitudinal section illustrating my improvements. Fig. 2 is a view in side elevation. Fig. 3 is a view in front end elevation. Fig. 4 is a view in horizontal sectional view, and Fig. 5 is a top plan view.

1 represents the casing of my improved apparatus, which contains within it combustion-chamber 2, cooler 3, scrubber 4, and purifier 5.

The combustion-chamber 2, which is made circular throughout its upper portion and rectangular at its lower portion, is provided with suitable walls 6, of masonry, and is supplied with fuel by any approved form of bell-hopper 7. In the lower rectangular portion of chamber 2 an inclined grate 8 is located and adapted to direct the ashes into water-seal pan 9, and a seal-plate 10 is provided at the forward end of the fire-chamber to prevent any entrance of air through the pan 9. A

pipe 11 communicates with the space below the grate 8 for the admission thereto of air and steam, as will be hereinafter described.

Gas is discharged from the upper end of chamber 2 through a neck 12 into one side of cooler 3. Said cooler comprises upper and lower horizontal boxes 13 and 14, respectively, connected by a series of vertical tubes or pipes 15, and removable covers 16 close openings in the top of upper box 13 directly over the tubes to permit ready cleaning of said tubes. These boxes 13 and 14 are provided with partitions 17, located about one-third of the distance from opposite ends, compelling the gas to pass down one set of tubes 15 to box 14, thence up through another set of tubes to box 13, and again down through another set of tubes to box 14, from which the gas passes through a pipe 18 into the bottom of a scrubber-chamber 4 below a grate 19^a therein, supporting charcoal or other like material. The tubes 15 of cooler 3 are surrounded by water in said cooler-chamber, supplied by a pipe 20 21, directing the water into the bottom of said chamber. The water, more or less heated by the gas, escapes at the upper end through a pipe 22, discharging the same through a perforated coil 23 in scrubber-chamber 4 onto the coke therein, compelling the water to pass in counter-current to the gas, and is carried off through a trap-pipe 24 at the bottom of said chamber.

The cooler 3 is provided with a laterally-elongated water-seal pan 25, which forms the bottom of box 14 and serves to catch all tar deposited by the gas and which can be removed from time to time through the lateral extensions of the pan at either side of the apparatus.

Scrubber-chamber 4 is divided from purifier-chamber 5 beside the same by a vertical-partition 26, which latter has an opening in its upper portion permitting the gas to enter chamber 5 and pass down through suitable material on a grate 27 therein and be sucked out through a pipe 28 to the engine, and suitable doors 29 are provided for chambers 4 and 5 to permit the ready access to said chambers.

Around the hottest portion of combustion-chamber 2 a water-tank 30 is located and supplied with water through pipes 20, 31, 32, 33, 34, and 35, and spigots 36 and 37, respectively, are provided on pipes 20 and 31 for supplying water to the pans 25 and 9. Steam generated in tank 30 passes through a pipe

38, past a throttle-valve 39 therein, through a pipe 40 41 to draft-pipe 11, and said draft-pipe 11 has an upright extension at one end, provided with a damper 42 in its upper end, the operation of said damper 42 and valve 39 being automatically controlled, as will now be explained.

The supply of air and steam to draft-pipe 11 is governed by the suction of the engine, the suction controlling the movement of a diaphragm in chamber 43, connected by a pipe 44 with suction-pipe 28. Connected with the diaphragm is a rod 45, pivotally connected at its other end with a walking-beam 46, one end of which is connected by a rod 47 with throttle-valve 39 and the other by a rod 48 with damper 42. As the suction of the engine increases rod 45 will be moved to the right, causing the walking-beam 46 to close steam-valve 39 and open air-damper 42, increasing the supply of air to the fire and causing the same to grow hotter and produce more gas. As the suction of the engine decreases rod 45 will be moved to the left, closing damper 42 and opening steam-valve 39, increasing the supply of steam under the grate of the combustion-chamber and causing the fire to diminish, and it will be observed that this mechanism at all times controls the proportion of air and steam to draft-pipe 11, and thereby regulates the intensity of the fire to suit the operation of the engine, and while I illustrate a diaphragm-chamber as the automatic means I do not wish to be restricted to this specific device.

A great many slight changes might be made in the general form and arrangement of parts described without departing from my invention, and hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. In a gas-producer, the combination of a casing, a combustion-chamber, a cooler, a scrubber, and a purifier-chamber all in said casing, and means connecting the same.

2. In a gas-producer, the combination of a casing, a combustion-chamber in one end thereof, a cooler adjacent to the combustion-chamber and in said casing, and scrubber and purifier chambers in the other end of said casing separated by a vertical partition, means for connecting the combustion-chamber with the cooler, means for connecting the scrubber and purifier with each other and means for connecting the cooler and scrubber.

3. In a gas-producer, the combination with a casing, of a combustion-chamber in said

casing, a cooler in said casing communicating with the combustion-chamber, a water-seal ash-pit for said combustion-chamber, 65 and a water-seal tar-receiving pan at the bottom of said cooler extending out beyond the casing to permit the removal of tar without disturbing the operation of the apparatus.

4. In a gas-producer, the combination with a combustion-chamber, a gas-cooler, and a purifier, of a water-tank or boiler in the combustion-chamber, a draft-pipe communicating with the bottom of said combustion-chamber, an air-damper for said pipe, a pipe 75 for directing steam from the boiler or tank into the draft-pipe, a valve in the steam-pipe, and means controlled by the suction of gas from the purifier and connected with the damper of the draft-pipe and the valve of the 80 steam-pipe for regulating the proportions of air and steam supplied to said draft-pipe.

5. The combination with a gas-producer, a grate in the combustion-chamber thereof, and a water tank or boiler in said combustion-chamber, of a draft-pipe communicating with the space beneath the grate, an air-damper at one end thereof, a pipe conveying steam from the boiler or tank to said draft-pipe, a valve in said steam-pipe, and automatic means controlled by the pressure of the gas issuing from the apparatus, for governing the operation of said valve and damper, to regulate the proportion of air and steam admitted to said draft-pipe. 95

6. The combination with a gas-producer, a grate in the combustion-chamber thereof, and a water tank or boiler around said combustion-chamber, of a draft-pipe communicating with the space beneath the grate, an air-damper at one end of said draft-pipe, a pipe conveying steam from the tank or boiler to the draft-pipe, a valve in said steam-pipe, and automatic means controlling the operation of the damper and valve. 100

7. The combination with a gas-producer, and a water tank or boiler in its combustion-chamber, a draft-pipe communicating with the space beneath the combustion-chamber, an air-damper at one end thereof, a pipe conveying steam from the tank or boiler to said draft-pipe, a valve in said steam-pipe, a diaphragm whose movement is controlled by the suction of gas from the apparatus, a walking-beam connected with the valve and damper, and a rod connecting said walking-beam with the diaphragm. 110

In testimony whereof I have signed this specification in the presence of two subscribing witnesses.

JAMES H. SWINDELL.
